UNITED STATES PATENT OFFICE.

ALFRED E. HOWARD, OF DETROIT, MICHIGAN, ASSIGNOR TO AMY ELAINE HOWARD, OF DETROIT, MICHIGAN.

GAS-BURNER.

SPECIFICATION forming part of Letters Patent No. 748,607, dated January 5, 1904.

Application filed May 23, 1903. Serial No. 158,510. (No model.)

To all whom it may concern:

Be it known that I, ALFRED E. HOWARD, a citizen of the United States, residing at Detroit, in the county of Wayne and State of Michigan, have invented a new and useful Gas-Burner, of which the following is a specification.

My invention is an improvement in gas-burners; and while my burner may be utilized for the purpose of cooking it is especially designed and adapted for the burning of gas in an open fireplace, my object being to provide a burner of this kind which will produce an open fire of a novel and attractive appearance and also to devise a burner of this type in which the maximum amount of heat produced by the burning gas will be thrown out into the room.

My invention consists of the novel features of construction and combination of parts hereinafter described, particularly pointed out in the claims, and shown in the accompanying drawings, in which—

Figure 1 is a perspective view showing the practical application of my device. Fig. 2 is a vertical section through my burner. Fig. 3 is a perspective view showing my burner as seen from below. Fig. 4 is a plan view of the top plate of my burner, and Fig. 5 is a perspective view of the horizontal partition.

In the drawings, A represents a gas-pipe having a tip A', secured to the pipe by the collar A'', and B represents a mixing-chamber having the appearance of an inverted bowl carried by the tip A'. A perforated plug A''' is secured on the tip and regulates by size of the perforation the amount of gas fed to the mixing-chamber. In the event that a larger supply of gas is desired the plug A''' may be removed and the device is used without it. Above and supported by the lower mixing-chamber B is a bowl-shaped chamber B', the two chambers being connected by a neck formed by the telescoping flanges B''. Air is admitted to the lower mixing-chamber B through the V-shaped slots B'', formed in the bottom of the said chamber. Supported by the upper mixing-chamber B' is a shallow rectangular tray or vessel comprising the bottom C, having a flat apertured central por-

tion and upwardly-sloping marginal portions. A slightly-convex cover C' extends over the vessel, and the edges of said cover are bent over the edges of the bottom C, as shown at C'', thereby securing an air-tight joint.

The tray or vessel is divided into upper and lower compartments C³ C⁴ by a horizontal partition C⁵. V-shaped notches are cut into the edges of this partition, forming blunt teeth C⁶, which are bent transversely and alternately upwardly and downwardly, the downwardly-bent portions resting on the sloping margins of the bottom C and the upwardly-bent portions serving to support the cover-plate C'. A central stub-post C⁷ is threaded into the partition C⁵ and supports the center of the cover, while posts C⁸ rest on the bottom C and extend through the partition C⁵ and aid in supporting the cover. The cover has a plurality of perforations C⁹, and its upper surface is surrounded by a low fence of wire scrollwork C¹⁰, though any ornamental border of wire, brass, or other metal can be used. The bottom C has a central opening C¹¹ and an annular depending flange C¹², serving as a short pipe opening into the lower compartment C⁸ and more effectually mixing the air and gas as they pass through it. Loose asbestos wool D or similar material is heaped upon the cover C', being held thereon by the border or fence C¹⁰.

The operation of my device is as follows: The pipe A being arranged centrally in an open fireplace or wherever it may be desired to use the burner, gas will pass upwardly into the mixing-chamber, and air will be drawn into the chamber through the openings B''. The air and gas will commingle during the passage through the neck B'', and the mixing of the two will continue in the chamber B', the mixing being further effected by their passage through the throat C¹¹, formed by the flange C¹². The commingled gas and air then spreads through the compartment C³ and passes up over the edges of the plate C⁵ into compartment C⁴ and through the openings C⁹, intermingling with the loose asbestos, and when lighted the flames of the burning gas will intertwine among the mass of asbestos, playing over the top and around

the sides of same and causing it to become incandescent, forming a fire of exceedingly beautiful and attractive appearance.

Having thus fully described my invention, 5 what I claim as new, and desire to secure by Letters Patent, is—

1. A burner of the kind described comprising a vessel divided into upper and lower chambers by a horizontal partition, a perforated cover over the upper chamber, means for admitting a combustible vapor into the lower chamber and around the edges of the partition into the upper chamber, non-combustible material loosely piled on the cover, 15 and means for retaining said material in place, as and for the purpose described.

2. A device of the kind described comprising a shallow vessel having a perforated cover, means for admitting gas and air into the vessel, a wire scrollwork carried by and extending around the cover, and asbestos piled loosely upon said cover.

3. A burner of the kind described comprising a gas-pipe opening upwardly into an inverted-bowl-shaped mixing-chamber, said

chamber having air-openings in its lower portion, an upper bowl-shaped mixing-chamber resting on the lower one, a shallow vessel resting on the upper mixing-chamber, said vessel having a perforated cover, and a flat, 30 horizontal partition dividing the vessel into upper and lower compartments, said partition having blunt teeth formed on its edges, the said teeth being bent alternately upward, and downward.

4. A device of the kind described comprising a rectangular, shallow vessel the bottom of said vessel having upwardly-sloping marginal portions, a slightly-convexed, perforated cover over said vessel, a horizontal partition 40 arranged in the vessel and having notched edges, a metal scrollwork around the upper edge of the cover, asbestos laid loosely on the cover within the scrollwork and means for admitting gas and air into the vessel beneath 45 the horizontal partition.

ALFRED E. HOWARD.
